TOILET ASSEMBLY

George Winter Kennedy, Philadelphia, Pa.

Application November 28, 1936, Serial No. 113,148

2 Claims. (Cl. 4-98)

This invention has to do with the art of toilet seats which are commonly included in the construction of a toilet assembly, and availed of by persons so that they may assume a sitting position while having a movement of the bowels.

It is well recognized by medical authorities that the ordinary comfortable sitting position is not nearly so helpful to a proper movement of the bowels as is the so-called "squatting position." Accordingly, this invention has in view, as an important objective, the provision of a toilet seat of the character described which is designed primarily to cause one to assume a "squatting position" when sitting on the same.

This end is attained by making the seat structure of a curved or bowed construction, and in order to further assure that the proper squatting position will be maintained by one using the seat the invention has in view, as a further more detailed objective, the provision of a back member which constitutes, for all effective purposes, a continuation of the seat structure. This back member is preferably detachably mounted in the structure of the toilet.

Various other more detailed objects and advantages will in part become apparent, and in part be hereinafter stated, as the description of the invention proceeds.

The invention, therefore, comprises a toilet assembly which includes a seat of a bowed or curved construction, and a back member which blends in and cooperates with the seat to cause one using the latter to assume a "squatting position."

For a full and more complete understanding of the invention reference may be had to the following description and accompanying drawing, wherein

Figure 1 is a side view, in elevation of a toilet assembly, made in accordance with the precepts of this invention,

Figure 2 is a front elevational view of the toilet shown in Figure 1, and

Figure 3 is a top plan view.

Referring now to the drawing, wherein like reference characters denote corresponding parts, a conventional toilet assembly is shown as comprising a toilet bowl 10, flush tank 11, and the

novel seat of this invention, which is designated 12.

As shown in the drawing, the bowl 10 is formed at its lower end with a flange 13 through which extend fastening elements 14 that anchor the bowl immovably in position. The upper edge of the bowl 10 is referred to as 15, and is of a curved or bowed formation; the bow extending from the front to the rear of the seat.

At the rear side the upper edge 15 of the bowl 10 terminates in a flat portion 16 on which is fastened, as by the fastening members indicated at 17, a back member 18.

The toilet seat 12 has a curvature corresponding to the top 15 of the bowl 10, and this seat 15 12 is hingedly mounted, as indicated at 19. From Figure 1 it can be readily seen that the back 18 merges in with the seat 12 and constitutes what is substantially a continuation thereof.

Figure 1 develops in dotted lines the "squatting 20 position" assumed by one using the seat, and which position is caused by the construction of the seat 12 and back 18. Dotted lines also bring out the position of the seat 12 when it is swung upwardly out of the way.

While a preferred specific embodiment of the invention is hereinbefore set forth, it is to be clearly understood that I am not to be limited to the exact construction illustrated and described, because various modifications of these details 30 may be provided in putting the invention into practice within the purview of the appended claims.

I claim:

1. A toilet assembly of the character described 35 comprising a toilet bowl formed with an upper edge curved from the front to the rear, a toilet seat conforming in curvature to the upper edge of the bowl, and a back member carried by the bowl.

2. A toilet assembly of the character described comprising a toilet bowl formed with an upper edge curved from the front to the rear, a toilet seat conforming in curvature to the upper edge of the bowl, and a back member detachably 45 mounted on the bowl and constituting a substantial continuation of the curved construction of the seat.

GEORGE WINTER KENNEDY.
